United States Patent Office

Des. 207,509
Patented Apr. 25, 1967

207,509

JUG

Laddie M. Thomka and Richard C. Cross, both of Midland, Mich., assignors to The Dow Chemical Company, Midland, Mich., a corporation of Delaware

Filed May 9, 1966, Ser. No. 2,210

Term of patent 14 years

(Cl. D58—5)

Fig. 5

Fig. 5

Fig. 4

Fig. 6

Fig. 7

FIGURE 1 is a side elevational view of a jug, showing our new design, the side opposite being a mirror image of the side shown;

FIGURE 2 is a rear elevational view thereof;

FIGURE 3 is a front elevational view thereof;

FIGURE 4 is a bottom view thereof;

FIGURE 5 is a top view thereof;

FIGURE 6 is a cross-sectional view thereof taken on line 6—6 of FIGURE 1; and

FIGURE 7 is a cross-sectional view thereof taken on line 7—7 of FIGURE 5.

The dominant features of our design reside in the portions shown by solid lines.

We claim:

The ornamental design for a jug, substantially as shown and described.
